TUBE STRUCTURE

Raymond H. Hobrock, Grosse Pointe, Mich., assignor to Bundy Tubing Company, Detroit, Mich., a corporation of Michigan

Application November 29, 1939, Serial No. 306,759

5 Claims. (Cl. 138—64)

This invention relates to tube structure, and it has to do with tubing made from strip metal stock.

The principal object of the invention is the provision of a novel tube structure comprised of at least two metal strips, one of which has corrosion resisting characteristics, while the other is for imparting strength and body to the tube, and need not have corrosion resisting characteristics. The corrosion resisting metal is usually relatively expensive, and in order to produce the tube cheaply this strip is preferably relatively thin. The structure is such that a strip of corrosion resisting metal, which may be relatively thin, forms the outer and inner surfaces of the tube, while the strength imparting strip is confined within the tube wall, and it gives to the tube wall, requisite thickness, body and strength. The strength giving strip may be relatively thick, but this is subject to variation, depending upon requirements as to strength, tube wall thickness, etc.

In carrying out the invention a number of corrosion resisting metals may be used for the one strip, such, for example, as nickel, copper, Monel metal, and in some instances, silver or gold, or various alloys of the above or similar metals, while the strip for giving body and strength to the tube may be a ferrous metal such as a low carbon steel. There may be instances, however, where a non-ferrous metal would be desirable as the strength giving strip, used probably in conjunction with a corrosion resistant strip of more expensive metal.

A tube structure for carrying out the invention is shown in the accompanying drawing wherein

Fig. 1 is a perspective view of a length of tube showing the end thereof.

Fig. 2 is an enlarged cross sectional view.

The structure of the tube is probably best illustrated in Fig. 2 wherein it will be seen that the tube wall is comprised of three plies or thicknesses. The ply 1 is, in the form of tube shown in the drawing, relatively thick and may be of ferrous metal. This ply is formed by one of the strips of stock. The other strip of stock has a considerably greater width, considered in the flat form, and it is fashioned so as to substantially completely envelop the ferrous metal strip. This is the corrosion resistant metal and is fashioned to form an outer ply 2 and an inner ply 3. An intermediate portion of this strip is fashioned to extend from the outer ply to the inner ply and so as to lie between the adjacent edges of the strength giving strip. This intermediate portion is shown at 4. The corrosion resisting metal is thus fashioned through substantially 360° to form the outer ply 2, and is formed with the offset portion 4, and fashioned substantially through 360° to form the inner ply.

The edges of the strength giving strip are preferably fashioned with contours of a substantially mating nature and which facilitate the formation of the offset 4. For example, one edge of the strip 1 is preferably rounded or formed on a radius as at 5 and provided with a relatively sharply extending edge 6, while the other edge in a mating fashion is similarly formed on a radius 7 with an extending edge 8. The offset 4 thus is not fashioned or bent too abruptly from the inner and outer plies, but joins thereto on generous curves. The edges of the strip 1 accordingly slightly overlap each other circumferentially, although spaced apart by the offset 4.

This tube may be fashioned from two strips of metal stock which are moved lengthwise from reels or rolls and fashioned into tubular form by a suitable tube forming mill, the general arrangement of which is well known to those versed in the art. The tube is sealed by uniting the contiguous surfaces of the plies and joints. Both the inner and outer plies of the corrosion resisting metal are united to the contiguous surfaces of the strength giving ply and the offset 4 is united to the edges of the strength giving ply. The edges of the corrosion resisting metal are brought into abutting relationship as at 9 and 10, with the curved portions substantially at the juncture of the offset 4 with the inner and outer plies. To this end the edges may be beveled or scarfed so as to meet the curved portions as indicated, although the bevel structure may be obtained by pressure in forcing the edges against these curved parts. The curved portions 5 and 7 of the strip 1 form a supporting base for the adjacent curved portions in the corrosion resisting strip so that considerable pressure may be applied at the edges. The tube is preferably sealed by the use of a molten sealing metal such as a soft solder, or a hard solder or brazing metals, the selection of which may be influenced by the requirements of the finished tube and by the particular metals employed in the tube. Soft solders are those which melt at a relatively low temperature, such as a mixture of tin and lead, while hard solders or brazing metals melt at higher temperatures, and accordingly thus would form a tube capable of withstanding higher temperatures in use. In some instances, as for example, where the strips forming the tube are of steel and Monel metal, the sealing metal may be substantially pure cop-

per, which, insofar as the present invention is concerned, may be called a brazing metal. In some instances it may be feasible to fuse the metal of the strips without a third sealing metal. 5 All these variations are covered by the language used in the appended claims which, in effect, state that the surfaces are united by a fused sealing metal.

Thus a tube is formed, the novel structure of 10 which employs a single strip for the inner and outer plies which completely envelops, except, of course, for the ends, the intervening strength giving strip. The corrosion resisting metal may, of course, be quite thin, but in this regard it is to 15 be pointed out that even though the corrosion resisting metal is thin, it is to be distinguished from a tubing which merely has a plating or coating of metal which may be formed, for example, by processes such as a hot dipping process or an 20 electroplating process. The corrosion resisting strip is thus a structural part of the tube and not merely a thin coating or plating. Tubing of this kind can be made in various sizes and may be used for fluid conducting purposes or for structural or semi-structural purposes, wherever corrosion resisting characteristics are desired.

I claim:

1. A tube comprising, a metal strip fashioned substantially into tubular form with its edges in 30 spaced facing relationship, another metal strip having a part fashioned around and contiguous to the outer surface of the first strip, a part extending between and contiguous to the edges of the first strip and a part fashioned into tubular form inside of and contiguous to the inner surfaces of the first strip, edge portions of the second strip being disposed in contiguous relationship to some of the said aforementioned parts of the second strip, the contiguous surfaces of the 35 strips and the contiguous surfaces of the edge portions and said parts of the second strip being united by fused sealing metal to seal the tube and substantially completely envelop the first strip.

2. A tube comprising a metal strip fashioned 45 into tubular form with its edges in spaced facing relationship, said strip being relatively thick to give the tube body and strength, another metal strip of relatively thin corrosion resisting metal having a part fashioned around and contiguous 50 to the outside surfaces of the first strip, a part extending between and contiguous to the edges of the first strip and a part fashioned into tubular form inside the first strip and contiguous to the inner surfaces thereof, edge portions of the 55 second strip being contiguous to some of the aforementioned parts of the second strip, the contiguous surfaces of the two strips and the contiguous surfaces of the edge portions and said parts of the second strip being united by fused sealing 60 metal to seal the tube and substantially completely envelop the first strip.

3. A tube comprising, a relatively thick ferrous metal strip fashioned into tubular form with its edges in spaced facing relationship, another strip 65 of relatively thin corrosion resisting metal hav-

ing a part fashioned into tubular form outside of and contiguous to the outer surfaces of the first strip, a part fashioned into tubular form inside the first strip and contiguous to the inner surface thereof and an intermediate integral part lying 5 between and contiguous to the edges of the first strip and connecting the inner and outer tubular forms of the second strip, edge portions of the second strip being disposed in contiguous relationship to some of the aforementioned parts of 10 the second strip, the contiguous surfaces of the two strips and the contiguous surfaces of the edge portions and the said parts of the second strip being united by fused sealing metal to seal the tube and substantially completely envelop the 15 first strip.

4. A tube comprising, a relatively thick metal strip fashioned into tubular form and having its edges disposed in spaced facing relationship, the edges being of beveled formation so as to overlap 20 each other circumferentially, another strip of relatively thin corrosion resisting metal having a part fashioned into tubular form around and contiguous to the outer surfaces of the first strip, a part fashioned into tubular form inside of and 25 contiguous to the inner surfaces of the first strip, and an intermediate integral part lying between and contiguous to the edges of the first strip and connecting the inner and outer tubular forms of the second strip, edge portions of the second strip 30 being disposed in contiguous relationship with some of the aforementioned parts of the second strip, the contiguous surfaces of the two strips, and the contiguous surfaces of the said edge portions and parts of the second strip being united 35 by fused sealing metal to seal the tube and substantially completely envelop the first strip.

5. A tube comprising, a relatively thick metal strip fashioned into tubular form and having its edges disposed in spaced facing relationship, the 40 edges being of beveled formation so as to overlap each other circumferentially, the contour of the strip substantially at the juncture where the edges meet the surfaces of the strip at an obtuse angle presenting a curved formation, another strip of 45 relatively thin corrosion resisting metal having a part fashioned into tubular form around and contiguous to the outer surfaces of the first strip, a part fashioned into tubular form inside of and contiguous to the inner surfaces of the first strip, and an intermediate integral part lying between 50 and contiguous to the edges of the first strip and connecting the inner and outer tubular forms of the second strip, said intermediate part joining with the inner and outer tubular formations on 55 curved lines where the same passes over the curved formations of the first strip, the edges of the second strip being beveled and disposed contiguous to the said curved portions of the second strip, the contiguous surfaces of the two strips and the contiguous surfaces of the edge portions and curved portions of the second strip being 60 united by fused sealing metal to seal the tube and substantially completely envelop the first strip.
